UNITED STATES PATENT OFFICE.

ALFRED L. WEISSENTHANNER, OF BAYONNE, NEW JERSEY, ASSIGNOR TO PHOENIX HERMETIC COMPANY, A CORPORATION OF NEW YORK.

SHEET-METAL CLOSURE.

1,129,150.

Specification of Letters Patent. Patented Feb. 23, 1915.

Application filed February 17, 1914. Serial No. 819,147.

To all whom it may concern:

Be it known that I, ALFRED L. WEISSENTHANNER, a citizen of France, and resident of Bayonne, in the county of Hudson and State of New Jersey, have invented certain new and useful Improvements in Sheet-Metal Closures, of which the following is a specification.

This invention relates to closures for jars and similar vessels, having relation more especially to that type of closures in which a single piece of sheet metal is struck up to form a crown portion having an integral depending circumferential flange which is provided at intervals with inward projections which are adapted to be engaged with and disengaged from inclined or spirally-disposed ribs or threads exteriorly of the neck of a jar or the like.

The object of my invention is to provide a closure of the type mentioned, which may be economically constructed of relatively thin metal and yet shall possess ample strength and rigidity together with sufficient resiliency to insure its ready application to and efficient locking engagement with the projections or threads of the vessel to be sealed, and this irrespective of ordinary structural imperfections of the interlocking parts.

According to my invention the closure in its preferred form is so constructed that its lower edge presents a series of relatively thin inturned locking projections the ends of which merge with and form a continuation of an inwardly and upwardly bent and pressed rim portion of the flange, whereby the material in the spaces between the locking projections is reinforced without increasing the body or thickness of the thread engaging portions of such projections and without impairing the requisite resiliency of the flange.

The precise nature and scope of my invention will appear from the following description and claims.

In the drawings—Figure 1 is a side elevation of my improved closure as applied to the mouth of a jar. Fig. 2 is a transverse vertical section of Fig. 1. Fig. 3 is a bottom view of the closure. Fig. 4 is a transverse section thereof, as on the line 4—4 of Fig. 3. Fig. 5 is a similar section as on the line 5—5 of Fig. 3. Fig. 6 is a similar section of the closure showing the inturned an-

nular lip before it is pressed against the inner wall of the flange.

My improved closure is struck up from a single piece of relatively thin sheet metal. In the form illustrated it comprises a crown 60 10 and an integral depending flange 11 the lower edge of which latter is bent inwardly and pressed upwardly to provide a reinforced segmental rim portion 12 having thin inwardly-projecting teats 13 which constitute locking projections. The segmental portions of the inturned edge are pressed hard against the inner side of the flange, and the ends of such members are caused to merge directly with the proximate ends 65 70 of the inwardly-projecting teats so as to support and brace the latter without increasing the body or thickness of their free thread-engaging edges. In the present instance the flange is represented as provided 75 with four locking projections of the character described, but it is to be understood that a greater or less number of such projections may be employed.

Preferably the flange of the closure is provided with vertical corrugations, as 14, which tend to stiffen the structure and also provide a "knurled" finger hold therefor as usual, the inner and outer convex portions of the corrugations being flush with the adjacent surfaces of the reinforced rim of the flange.

By the construction above described the external appearance of the closure is practically unaffected by the presence of the reinforced rim and the locking projections, for the reason that the edge fold is on the interior of the flange and the basal portions of the projections are flush with the lower edge of the rim or substantially so. The 90 95 projections 13 being relatively thin and in close relation to the edge of the rim readily adapt themselves to the threads of the vessel for wedging engagement therewith, and at the same time the reinforced segmental 100 portions of the rim possess sufficient resiliency to enable them to adjust themselves to ordinary structural imperfections or variations in the opposing surfaces of the vessel to which the closure is applied.

The closure is usually provided with an internal sealing disk 14' (Fig. 2) which is forced down upon and around the mouth of the jar when the closure is applied thereto.

In manufacturing my improved closure I 110

first produce a circular blank of the requisite diameter. I then shape the blank to produce the crown 10 and the depending flange 11. I then turn the lower edge of the flange inwardly to produce the annular lip shown in Fig. 6. I then press this lip upwardly against the inner side of the flange, excepting at the intervals where the teats are to be located, such teats thus resulting from the unfolded portions of the lip as seen most clearly in Fig. 4.

I claim—

1. A sheet metal closure the flange whereof is provided at its lower edge with a series of inwardly-extending locking projections and intervening segmental portions, the latter being reinforced on the inner side

of the flange by inwardly and upwardly-bent rim portions which merge with and brace the ends of the said projections.

2. A sheet metal closure whereof the flange is provided at its lower edge with a thin inturned locking projection and with an inwardly and upwardly bent and pressed rim portion which merges with and forms a continuation of the ends of said projection.

Signed at New York in the State of New York this thirteenth day of February A. D. 1914.

ALFRED L. WEISSENTHANNER.
